(57) **CLAIM**

We claim the ornamental design for a nasal dilator, as shown and described.

DESCRIPTION

FIG. 1 is a perspective view of the nasal dilator showing my new design;

FIG. 2 is a top view thereof;

FIG. 3 is a bottom view thereof;

FIG. 4 is a side elevational view thereof, both sides being the same; and,

FIG. 5 is an end elevational view thereof, both ends being the same.
